Primary Examiner—Celia Murphy*Attorney, Agent, or Firm*—Marshall A. Lerner, Esq.; Bradford E. Mattes, Esq.; Kleinberg & Lerner, LLP[57] **CLAIM**

The ornamental design for a combined shoe bottom and periphery, as shown and described.

DESCRIPTION

FIG. 1 is a right side elevational view of a combined shoe bottom and periphery showing my design. The broken line showing of the shoe in FIG. 1 is for illustrative purposes only and forms no part of the claimed design;

FIG. 2 is a bottom plan view thereof;

FIG. 3 is a left side elevational view thereof;

FIG. 4 is a front elevational view thereof; and,

FIG. 5 is a rear elevational view thereof, the top being unshaded because it forms no part of the claimed design.
